CONTAINER FOR CORROSIVE SUBSTANCES

Percy E. Knudsen, Pittsburgh, Pa., assignor to
 Pittsburgh Plate Glass Company, Allegheny
 County, Pa., a corporation of Pennsylvania

Application June 5, 1943, Serial No. 489,787

3 Claims. (Cl. 206—2)

The present invention relates to the provision of corrosion-resisting tanks or receptacles and it has particular relation to the construction of such tanks or receptacles from glass.

One object of the invention is to provide tanks or receptacles of relatively large size and of high strength, but consisting substantially solely of glass.

A second object of the invention is to provide tanks of the foregoing type, which are relatively simple and easy to construct.

These and other objects of the invention will be apparent from consideration of the following specification and the appended claims.

It has heretofore been recognized that glass is highly resistant to corrosion by most chemical agencies, such as most acids and oxidizing agents. Because of this property, bottles and other small containers for such materials have commonly been prepared from this material. However, because of difficulties of manufacturing glass articles of large size and of adequate strength it has heretofore been virtually impossible to employ glass as a structural medium in the fabrication of large vats and tanks, such as are employed in the metallurgical industries for plating, pickling and cleaning operations. Tanks for these purposes therefore have commonly been constructed of wood, concrete, metal and the like. These obviously are not satisfactory for the purpose, because they are gradually decomposed by many active chemical agencies, such as acids of the nature of sulphuric acid, chromic acid, phosphoric acid and the like, which are commonly employed in the chemical industries in various treating operations.

In accordance with the provisions of the present invention it is proposed to fabricate containers of relatively large size and consisting almost wholly of glass by building up the walls of the containers of narrow, flat strips or plates of glass of greater width than thickness, laid face to face and having alternate projecting and recessive end portions providing dentations interleaved with and connected to similar portions of the contiguous side walls.

For a better understanding of the invention reference may now be had to the accompanying drawings in which like numerals refer to like parts throughout.

In the drawings

Fig. 1 is a plan view looking downward upon a tank constructed in accordance with the provisions of the invention;

Fig. 2 is a sectional view taken substantially upon the line II—II of Fig. 1;

Fig. 3 is a fragmentary view showing on a larger scale a detail of the corner construction of the tank shown in Fig. 1;

Fig. 4 is a fragmentary view illustrating the manner in which the glass plates constituting the side walls of the tanks are interleaved at their corners.

10 In a tank constructed in accordance with the provisions of the present invention, side walls 10 and 11 and end walls 12 and 13 are supported upon a glass bottom plate 14, preferably of tempered glass. The bottom plate may rest upon setting strips 16 of polished and tempered or annealed glass, which are disposed under all of the edges of the plate 14 and which also may be spaced at suitable intervals under the entire area of the plate. These setting strips preferably rest upon solid glass blocks 17, which are carefully levelled upon a suitable supporting surface in such manner as to obtain bearing contact of all of the setting strips with the plate 14.

Side walls 10, 11, 12 and 13, as best shown in 25 Fig. 3, are built up of narrow strips or bars 18 of polished glass plate, which also may be tempered by the so-called "Herculite" process, which involves the sudden chilling of the plates (already cut and formed) while they are heated to 30 a temperature approximately of softening of the glass. The faces of these plates preferably are bonded together by means of a corrosion resistant cement, such as that provided by sodium silicate, asphalt or any other cementing material, which 35 will resist the attack of the materials to be contained in the tank.

It will be evident from Fig. 4 and also from Fig. 1 that all of the plates or bars 18 upon a side wall are of a single length. In order to provide 40 projecting end portions or dentations 19 to interleave with similar portions of the contiguous wall, the plates are alternately slightly staggered to the right and left (longitudinally of the plates) to provide a dovetailed effect. It will be observed 45 in Fig. 1 that the recessively set end portions of the bars are slightly inwardly bevelled as indicated at 21 to receive a corrosion-resisting cement substance, such as asphalt or a resistant inorganic cement.

50 The projecting end portions of the plates are bored as indicated at 22 to receive vertical tie bolts 23 of nickel-chromium, steel or other corrosion-resisting material. Preferably the holes 22 are of slightly larger diameter than the bolts 55 and the space is filled with a suitable corrosion-

resisting cement that provides a bearing between the inner walls of the bore and the surface of the bolt. It is to be observed that the block 17 beneath the lower extremity of the bolt is recessed to receive nut 24, held to permit thermal expansion and contraction and from rotation upon the bolt by means of a lock washer 26 bearing at its upper face against a washer 27 of asbestos or other suitable material. The upper plate 18 of the plates 18 is also slightly recessed as indicated at 28, to receive the lower portion of a washer and nut assembly 29. This assembly is covered and protected by a cup 31 of glass or other corrosion-resisting material embedded in a coping bar or rail 32, which is recessed or channeled as indicated at 33 snugly to fit over the top edge of the wall. This coping extends entirely about the upper edge of the tank.

In order more securely to hold the recessively set end portions of the upper plates in the walls, 20 they together with the contiguous plates beneath are bored to receive stud bolts 34 having upper nuts and washer assemblies 36, which are also enclosed in glass cups 37, set in a manner similar to the cups 31. The lower extremity of the bolts are also provided with nut and washer assemblies 38 set in recesses 39 in the contiguous glass plates.

Smaller sizes of tanks constructed in accordance with the foregoing disclosure may conveniently be assembled at the factory and shipped in completed form to the user. However, under some conditions and for the larger sizes of tanks it may be more convenient to build the tanks up in situ upon their permanent foundations. It will be apparent that the tanks may be constructed with side walls of substantially any desired thickness. Therefore, any degree of strength required may be obtained. All exposed portions of the tank consist essentially of glass or corrosion-resisting cement and the few metal parts required are completely protected either by the glass or by the coping rail 32. This latter, of course, acts as a buffer to protect the edges of the glass walls from being chipped. The rail may be formed of wood, rubber or other suitable material which can easily be replaced periodically as it deteriorates under wear and the action of corrosive chemicals. It is manifest that the glass strips 18 can be manufactured exceedingly simply merely by cutting larger plates of glass after grinding and polishing to appropriate length and suitably boring the end portions to receive the anchoring bolts.

The forms of the invention herein shown and described are to be considered merely as exemplary. It will be apparent to those skilled in the art that numerous modifications may be made therein without departure from the spirit of the invention or the scope of the appended claims.

What I claim is:

1. A container for corrosive substances comprising narrow plates of glass laid up flat in face

to face contact to provide side walls, said plates being bonded together at their contiguous faces by means of a corrosion resistant cement, the plates upon a side wall extending from corner to corner of the container and being of the same length and alternately being staggered to the right and left in the plane of the side wall in which they are disposed to provide dentures intermeshing with similar dentures from a contiguous side wall, the projecting end portions of the plates being bored to receive through bolts locking the side walls together the bolts further having nuts threaded upon their upper extremities, the nuts being covered by inverted glass cups, the lower edges of the cups being countersunk into the upper face of the dentures provided by the uppermost plates of the side walls in order to exclude corrosive fluids from contact with the nuts.

2. A container for corrosive substances comprising narrow plates of glass laid up flat in face to face contact to provide side walls, said plates being bonded together at their contiguous faces by means of a corrosion resistant cement, the plates upon a side wall extending from corner to corner of the container and being of the same length and alternately being staggered to the right and left in the plane of the wall in which they are disposed to provide spaced projecting dentures intermeshing with similar dentures from a contiguous wall, the projecting dentures being bored to receive through bolts, said bolts being set in cement disposed in the bores of the projecting dentures the bolts further having nuts threaded upon their upper extremities, the nuts being covered by inverted corrosive resistant cups having their lower edges sealed in countersunk portions in the upper faces of the upper dentures whereby to protect the nuts from corrosion.

3. A container for corrosive substances comprising narrow plates of glass laid up flat in face to face contact to provide side walls, said plates being bonded together at their contiguous faces by means of a corrosion resistant cement, the plates in a side wall extending from corner to corner of the container and being of the same length and being alternatively staggered to the right and left in the plane of the side wall in which they are disposed to provide dentures intermeshing with similar dentures from a contiguous side wall, the projecting end portions of the plates being bored to receive through bolts locking the side walls together, the bolts further having nuts threaded upon their upper extremities, the nuts being covered by inverted glass cups, the lower edges of the cups being countersunk into the upper faces of the dentures provided by the uppermost plates, a coping of resilient material disposed upon the upper edges of the side walls, said coping having recesses formed therein fitting over the upper portions of the cups.

PERCY E. KNUDSEN.
